UNITED STATES PATENT OFFICE.

CHARLES WILBUR MEGUIAR, OF SONORA, KENTUCKY.

MEASURING CONTAINER FOR DENTAL ALLOYS OR THE LIKE.

Application filed February 8, 1917. Serial No. 147,509.

To all whom it may concern:

Be it known that CHARLES WILBUR MEGUIAR, a citizen of the United States, residing at Sonora, in the county of Hardin 5 and State of Kentucky, has invented certain new and useful Improvements in Measuring Containers for Dental Alloys or the like, of which the following is a specification, reference being had therein to the accompanying drawing.

This invention relates to containers for dental alloys or the like, and more particularly to a container of this character adapted to discharge uniformly measured 10 quantities of the alloy at the will of the user.

For a great many years in the dental art, it has been substantially the uniform practice to utilize ordinary glass bottles with a cork or similar closure as containers for 15 dental alloys, and it has been the custom of the dentist, as occasion demands in preparing an amalgam, to discharge from the mouth of the bottle what he considered to be the proper amount of alloy to become 20 intimately connected with the mercury to form the amalgam. Usually the amount of alloy discharged from the bottle is determined by guess-work on the part of the user, though in some instances, the more 25 careful dentists have resorted to balances and scales, involving additional expense and time.

Many objections and disadvantages incident to the use of the glass bottle as the container for dental alloys, have long been 30 recognized by those skilled in the art to which the invention relates, among which may be briefly mentioned the following.

Because of the material of which the containers are made, i. e. glass, the same are 35 subject to breakage in being transmitted from place to place as through the mails or by express and in the use of the same by the dentist they are apt to become upset or fall 40 upon the floor and become destroyed with the incident loss of the alloy. These containers are not only expensive because of the construction thereof, but the weight of the same is an item in the consideration of 45 transportation charges. Again, the containers may, if desired be refilled by an unscrupulous party with an inferior grade of alloy and possibly palmed off as the original 50 standard grade originally placed in the bottom by the manufacturer. In the use of the ordinary bottle container, the dentist often

leaves the opening exposed by the removal of the cork closing means which from a sanitary point of view is highly objectionable, the open mouth of the bottle forming 60 a convenient repository for the collection of dust, etc.

Still further, assuming that the dentist discharges from the bottle more material than is necessary for the desired mixture, 65 any surplusage is either necessarily wasted, or if gathered up and replaced in the bottle, a highly objectionable operation from the standpoint of cleanliness, etc., will result, and this factor is quite important consider- 70 ing the use to which alloy is put.

It may therefore be said to be among the objects of the present invention to overcome the above and many other objectionable characteristics incident to containers as at present employed, by the provision of a simple, inexpensive, sanitary, and substantially non-breakable container adapted to discharge measured quantities of the material at will, and of a character to make exceedingly difficult a refilling of the container with dental alloys or the like.

A further object of the invention is to provide a container for the described and similar purposes, which is light in weight, 85 thus materially reducing both the cost of production and transportation charges, also a container of transparent material, whereby the contents may be observed at all times, and said material preferably being tough 90 and yieldable whereby to overcome possible breakage and incident loss of the material should the container become jarred, upset, fall upon the floor, etc.

A further object of the invention is to provide a container with novel and improved means for closing the outlet thereof whereby to protect the contents from outside influence to a large extent, and whereby to effectively close the container against accidental discharge of the material.

Another feature of the invention resides in the provision of means whereby the container may be supported in an upright position, and whereby the outlet from the container is arranged in the bottom wall or base thereof, to the end that said outlet is protected against the inlet of dust, dirt or the like during use of the container and after the removal of the closure means for the 110 outlet.

It is also a feature of the invention to

provide a container of the character described, adapted, in the operation thereof, to accurately discharge measured quantities of the contained alloy or the like, the amount of discharge being substantially uniform at all times until all of the material within the container has been discharged. It is also contemplated by the invention to provide a container of the character described with a novel construction of outlet passage which conveniently takes the form of an internal tube opening at one end to the outside and opening at its opposite end into the container whereby to constitute an inlet for the material to be discharged, which said tube preferably tapers from the inlet to the discharge end thereof, whereby to facilitate the ready discharge of the material without the possibility of any of the material clogging adhering to the sides of said tube in the discharging operation, and also facilitating the positioning of the closure means for the outlet to be more particularly referred to hereinafter.

More particularly, the invention includes a tubular container having a closed end and an opposite apertured end, and an internal discharge tube having an inlet opening adjacent the closed end of the container and an outlet opening to register with the aperture in the open end of the container, with means whereby the container may be supported in an upright position with the closed end of the same uppermost, with the result that said closed end and the inlet end of the internal tube will remain substantially free from accumulation or any compacting of the alloy at these points during periods of rest.

Still other and further improvements, and novel details in the construction and arrangement of the various parts of the invention will be appreciated from the description to follow, which, for a clear understanding of the invention is to be considered in connection with the accompanying drawings, forming a part hereof, and wherein is disclosed, for the purpose of illustration, a convenient and satisfactory embodiment of the invention, though in this connection it is to be borne in mind that certain minor changes in the details and construction and arrangement of parts may be resorted to without departing from the spirit or contemplation of the invention.

In the drawings:—

Figure 1 is an elevation of the improved capsule or container with one end removed.

Figure 2 is a similar view with the end in place.

Figure 3 is a vertical section of a capsule complete showing the alloy contents.

Figure 4 is an elevation of the tubular discharge conduit, prior to its application

to the body portion of the container or capsule illustrated in Figure 3.

Figure 5 is a cross section substantially on the line 5—5 of Figure 2.

With more particular reference to the drawings, wherein like reference numerals refer to corresponding parts throughout the several views, 1 is a body part, the same being preferably in the form of a cylindrical tube, one end connecting with a slightly enlarged annular offset part or base 2 and the opposite end connecting with a cone-shaped part 3, the apex of which latter is arranged preferably substantially in alignment with the longitudinal axis of the body part 1, the wall of the body part 1 conveniently tapers from the annular part 2, inwardly to its point of connection with the cone part 3, not only to assist in the feeding of the material towards the pointed terminal of the cone in the discharging operation, but also to facilitate the removal of the body part from the mould or the like while in course of construction of the same. The tapered formation of the body part also assists in maintaining the container in an upright position against accidental tilting and upsetting when placed upon a suitable support with the annular base 2 in position thereon. In the construction of the container, the lower end wall together with the discharge conduit is conveniently formed separately from the body portion as illustrated more particularly in Figure 4 of the drawings, the lower end wall being conveniently cone-shaped as illustrated at 4 and connecting at its outer end with an annular flange 5 of substantially the same as, or slightly less than the depth of the annular base 2 of the body part, though of slightly less diameter whereby to be readily inserted within and contact with the inner surface of the annular base 2, the shoulder 2 of the body part which connects with the annular part 2 forming an abutment to limit the inward movement of the conical end 4 in assembling the latter. The conical bottom member or end wall 4 is provided with a central aperture 6 in alignment with the apex of the opposite conical end 3 of the container. Surrounding said aperture 6 is an internal discharge tube 7 which latter is connected to and preferably constitutes an integral extension of the lower end wall 4, the said tube projecting to a point above the point of connection between the body part 1 and the conical end 3 and terminating at a point spaced inwardly from the apex of the end 3, whereby to provide an annular passage-way 8 between the open end 7a of the tube 7 and the closed end 3 of the body part. The length of the internal tube 7 and the degree of space between the open end 7a thereof and the closed end 3 of the body

portion, will vary according to the amount of material to be discharged through the tube 7.

While the flange 2 of the body part 1 and of the cone-shaped end 4 may be secured to one another in various ways and be within the contemplation of my invention, in the embodiment of the invention illustrated, the lower end of said flange 2 is preferably 10 slightly upset inwardly thereby forming an interlocking and overlapping connection or joint 5^a closed against the accidental discharge of the material at this point and protecting the contents from the outside 15 influence to an appreciable extent.

It is desirable, not only in the shipping of the capsule but after each use of the same, to effectively close the discharging outlet of the same as well as to close the 20 passage-way 8 or the means of communication between the interior compartment of the container and the open inlet end of the discharge tube 7. With this in view, I preferably provide a closure in the nature 25 of a plug or stopper 9, which latter is preferably formed of yieldable material such as cotton, which is at all times accessible to the dentist because of the various uses to which cotton is put by him. In assembling 30 the closure, the same is forced through the tube 7 and into contact with the inner surface of the terminal of the cone-shaped end 3 of the body part, the closure 9 being forced into wedging contact with said surface and overlapped relation with the inlet 35 end of the tube 7, as more clearly illustrated in Figure 3 of the drawing. When in position, this closure will prevent any accidental discharge of the material through 40 the tube 7 or any accumulation of the material upon the inner surface of the cone-shaped end 3 of the container or the inlet end 7. It will be appreciated that each time the closure is removed, it will serve as a 45 cleansing medium for the surfaces contacted therewith, and in the application or removal of the closure the ordinary dental wire or broach generally employed in inserting or removing cotton may be re- 50 sorted to.

All of the parts of the container excluding the closure means are preferably formed of thin, light, flexible, transparent material, and I preferably utilize in this connection 55 gelatine or gelatinous composition, which is of especial advantage not only because of the reduced expense, the ease of manufacture, and other equally important attributes, but the further fact that the same is un- 60 affected by and has no detrimental effect upon the dental alloy.

When the parts are formed of gelatine or the like they may after the dry alloy 10 is placed in the body be readily united so 65 as to form a substantially sealed joint by

turning the edge of the flange 2 inwardly preferably under heat to the condition illustrated in Figure 3. The internal discharge tube 7 preferably tapers inwardly from the base thereof to the inlet end whereby to facilitate the ready insertion of the tube through the alloy and also discharge of the material through the tube and prevent clogging or adherence of the alloy to the inner surface of the tube which would prevent accurately measured quantities to be discharged at each operation. 75

The normal position of the container when not in use is as illustrated in the drawings, upright with the pointed closed end uppermost, and in this position it will be noted that the outlet or discharge end will be effectively protected against the admission of dust, dirt, or the like even assuming that the closure 9 remains removed from the container after use. Then again, since the discharge end of the tube 7 is spaced upwardly from the annular base 2 of the container, the discharge end of the tube not being in contact with the surface is protected from the accumulation at this point of foreign materials which might be discharged by the contact therewith of the alloy as leaving the container. 80 85 90

In the use of the device, the operator grasps the same and after removal of the closure 9 inverts the position of the container when the material will flow downwardly through the passage 8 filling the space between the inner surface of the pointed terminal part of the cone 3 and the inlet end of the tube 7. Thereupon, the container is quickly repositioned with the conical end 3 uppermost when a measured quantity of the material will freely pass through the tube 7, 105 and be discharged from the lower end of the container. By reason of the fact that the closed end 3 is in the form of a cone with a substantially pointed apex, there is no likelihood of the material shifting laterally from the seat or pocket formed by the apex of the cone, but the same will be positively discharged downwardly in direct alinement with the inlet end of the tube 7, with the result that the measurements will 110 be uniform at all times. The peculiar shape of the closed terminal 3 also makes possible the continuous discharge of the material in uniform measurements until all of the material within the container has become ex- 115 hausted. 120

It has been appreciated that the present container while not necessarily limited to such use is adapted more particularly to receive dental alloys which, as will be understood by those familiar with the art, are peculiar in that they tend to cling or adhere to surfaces, and to condense or settle compactly when allowed to continue in a space. Since the closed conical end 3 of the con- 125 130

tainer provided by me is arranged uppermost, there will be no condensed accumulation or packing of the material adjacent to or around the inlet end of the tube 7, as is apt to be the case should the closed end and the inlet end of the discharge tube 7 be arranged at the base rather than at the top of the container. As the period of time between operations vary, this is essential to uniform discharges of alloy.

Any suitable means other than the hands of the operator may be operatively connected to the container for moving or oscillating the same to perform the discharging function, such for instance as illustrated and described in an application filed by me concurrently herewith. When such means are resorted to, however, it is quite desirable in the normal position of the parts to maintain the container with the closed conical portion 3 disposed uppermost, for the reason herebefore referred to.

What I claim is:—

1. A capsule for dental alloys and the like comprising a tubular member having a base or bottom and a cone-shaped closed upper end, said base or bottom being adapted to support the capsule in upright position, and an internal tube projecting upwardly from said base and terminating short of said upper closed end, said internal tube being open at its top and bottom, and the lower end of the tube having an opening constituting an outlet from the container.
2. A container of the character described, comprising a tubular body portion having a cone-shaped closed upper end and a lower end with a centrally disposed aperture, and an internal discharge tube surrounding said aperture and projecting upwardly from the lower end with an inlet opening adjacent to but spaced from the closed upper end at the center thereof, and said lower end of the body portion being adapted to rest on a suitable surface whereby to maintain the closed opposite end in uppermost position and whereby to protect the open end of the discharge tube.

3. A container for alloys or the like, comprising a tubular member of thin, yieldable, transparent material having a closed conical end and an opposite end with an aperture therethrough, and an internal tube of transparent material surrounding said aperture and projecting inwardly to a point adjacent the inner surface of the terminal of said conical closed end, the said opposite end of the tube with said aperture being adapted to rest upon a surface and thereby constitute means for preventing the entrance of dust or foreign matter through said aperture when not in use.

4. A container for dental alloys and the like adapted to discharge measured quantities thereof comprising a cylindrical tubular container of thin, yieldable, transparent material having an integral closed conical end and an opposite end with a central aperture in alignment with the apex of the cone-shaped end, said opposite end being constructed to rest upon a surface and maintain the closed end of the container uppermost, and an internal discharge tube integral with the open end and surrounding the aperture in said open end of the container, said tube projecting to a point adjacent the apex of the cone-shaped end and having an inlet opening at this point, and an interlocking engagement between the body portion of the container and said apertured end.

5. A container for dental alloys and the like, comprising a tubular member having a cone-shaped closed upper end and a substantially cone-shaped lower end with the apex disposed uppermost, said lower end having an integral upwardly projecting discharging tube open at its opposite ends, and with the upper end thereof spaced a slight distance below the upper closed end of the container, said discharging tube connecting with said lower end at the apex thereof, substantially as and for the purpose described.

In testimony whereof I hereunto affix my signature.

CHARLES WILBUR MEGUIAR.
